ELECTRON TUBE

Harold E. Sorg, Redwood City, Calif., assignor to
Eitel-McCullough, Inc., San Bruno, Calif., a
corporation of California

Application January 22, 1945, Serial No. 573,875

8 Claims. (Cl. 250—27.5)

1

My invention relates to an electron tube having an external anode.

It is among the objects of my invention to provide improved means for cooling the external anode of a tube.

Another object is to provide an improved tube structure adapting it for operation at higher frequencies.

The invention possesses other objects and features of advantage, some of which, with the foregoing, will be set forth in the following description of my invention. It is to be understood that I do not limit myself to this disclosure of species of my invention as I may adopt variant embodiments thereof within the scope of the claims.

Referring to the drawings:

Figure 1 is a vertical sectional view of a tube embodying the improvements of my invention.

Figure 2 is a sectional view showing the anode portions of the tube and illustrating a modified cooling arrangement; and

Figure 3 is a similar view showing another modification.

In terms of broad inclusion, my electron tube comprises a metallic external anode forming portions of the tube envelope. In my preferred tube the anode is of reentrant construction to provide a compact electrode assembly. The grid of the tube is mounted on a terminal ring below the reentrant anode, and the cathode is preferably supported on a concentric stem structure. In one type of anode cooling arrangement embodying my invention a finned metal cooler is mounted on the anode with a heat conducting core extending into the reentrant portions of the anode. The cooler is inserted in a conduit through which a cooling fluid such as air is forced, this conduit preferably being electrically connected to the anode and forming part of the anode circuit. In a modified tube structure adapted for increased anode dissipation, a jacket is arranged on the anode into which a cooling fluid or refrigerant under pressure is expanded to lower the temperature. The jacketed cooler construction may be used with tubes having various types of anode design, although I prefer to employ the reentrant type of anode with the jacket arranged to extend into its reentrant portion. The fluid duct or ducts connected with the jacket are preferably arranged within the electrical conduit terminating at the anode.

In greater detail, and referring to Figure 1 of the drawing, my improved electron tube comprises a metallic reentrant anode forming the upper end portions of the tube envelope and having

2

a cup-shaped cylindrical body 2 and an upturned end flange 3 terminating in a downturned sealing rim 4. This folded type of anode structure positions the lower end of the anode down within the envelope for compactness of the electrode assembly. The tube illustrated is a triode including a grid 6 and cathode 7, these electrodes being supported from the lower portions of the envelope and projecting upwardly into anode body 2.

10 Grid 6 is connected with and supported by a metallic terminal ring 8 sealed to the lower end of an annular vitreous envelope section 9, the upper end of which is sealed to rim 4 of the anode. The infolded anode structure provides sufficient 15 spacing between rim 4 and terminal ring 8 for insulation purposes, yet keeps the electrical path from ring 8 to grid 6 relatively short. This is important for high frequency operation. The remainder of the grid support preferably comprises 20 a transverse apertured disk 11 carrying a conical bracket 12 to which the grid is secured.

Cathode 7 is connected with and supported by a stem structure preferably comprising a tubular metallic stem member 13 and an inner concentric 25 stem member 14 held by a spacing ring or bead 16 of vitreous material sealed between the members. Outer stem member 13 has a metallic flange 17 sealed to an annular vitreous envelope section 18, the latter being sealed at its upper end to terminal ring 8. Cathode 7 is preferably of the filamentary type comprising a thoriated tungsten filament secured at its lower end to stem member 13 and at its upper end to a center rod 19 projecting from stem member 14. It is understood of course that an oxide coated cathode may be used instead of the thoriated type.

Inner stem member 14 is preferably hollow and is ported into the envelope through opening 21 for purposes of evacuating the tube. A glass 40 tubulation on the lower end of member 14 is sealed off at tip 22 after the exhaust. The coaxial type of stem structure above described is preferred because it further improves the tube for high frequency work.

45 Heat is removed from the anode by a cooler having a core 23 of good heat conducting material, such as copper, encircling anode body 2 and extending into the reentrant space between the anode body and upturned flange 3. The 50 cooler also includes an annular finned section 24 of metal secured to core 23 and having radial fins 26 extending outwardly from the anode body above flange 3. A curved bottom plate 27 on section 24 serves to direct a cooling fluid outwardly 55 at the base of the fins.

One important advantage of the reentrant anode and cooler combination above described is that heat conducting core 23 contacts the full length of the anode body, including that portion projecting into the envelope, and serves to conduct heat uniformly away from the anode. As a result the advantage of an inwardly projecting anode structure for high frequency work is obtained without decreasing the heat dissipation properties of the tube, it being understood that the power output of a tube is proportional to its anode dissipation capabilities.

While I have shown anode body 2 and collar core 23 as separate pieces, it is understood that they may be formed integrally. The separately formed anode of sheet material is preferred however because the fabrication problem is simplified and it is possible to heat the anode on the pump to a higher temperature for outgassing purposes, it being preferred to apply core 23 to the anode after the tube has been evacuated.

As shown in Figure 1, anode body 2 with its cooler assembly is inserted in the end of a conduit 28 so that fins 26 lie in the space between the anode and conduit. A cooling fluid such as air is forced down through the conduit so that it flows past fins 26 and out through openings 29. Conduit 28 is metallic and makes electrical contact with the anode through the cooler so that the conduit also functions as the anode line or circuit for the tube.

In a modified anode cooler structure shown in Figure 2 a metallic jacket 31 is fitted on anode body 2, with the lower end of the jacket extending into the reentrant portion of the anode. This jacket is preferably inserted into the lower end of anode circuit conduit 28. In this cooling system jacket 31 provides an expansion chamber, a suitable pressure fluid being expanded into the jacket through a small orifice in nozzle 32. A duct 33 in conduit 28 connects nozzle 32 with a suitable source 34 of the pressure fluid. Duct 33 is arranged in conduit 28 so as not to interfere with the electrical properties of the anode circuit. The expanded fluid is discharged to the atmosphere from jacket 31 through outlets 36.

Another cooler structure is illustrated in Figure 3 which includes a second duct 37 connected with jacket 31 for returning the low pressure fluid back to source 34. In this case the source 34 preferably includes a compressor for recompressing the fluid. The cooling medium or refrigerant may be any suitable fluid such as sulphur dioxide or methal chloride.

It will be seen that the tube structures shown in Figures 2 and 3 both comprise a metallic anode having a heat dissipation portion projecting externally of the envelope; a fluid expansion chamber thermally connected with the projecting portion of the anode; and means for expanding a pressure fluid into the chamber. As previously mentioned, the hollow end of the anode unit preferably extends within the tube envelope. These structures have a decided advantage for high power high frequency tubes because it is possible to achieve large heat dissipations in tubes of relatively small size.

I claim:

1. An electron tube comprising a sealed-off evacuated envelope, a reentrant metallic external anode forming the upper portion of the tube envelope and having a cylindrical body and an upturned end flange, and a cooler on the anode having a heat conducting core encircling the body and extending into the space between the

flange and the body, said cooler having fins extending outwardly from the core and disposed intermediate the flange and the upper end of the anode.

- 5 2. An electron tube comprising a sealed-off evacuated envelope, a reentrant metallic external anode forming the upper portion of the tube envelope and having an upturned end flange carrying a sealing rim disposed above the lower end of the anode, a grid terminal ring forming part of the envelope wall below said sealing rim, a vitreous envelope section sealed between said rim and terminal ring, cathode conductor means at the lower end of the envelope, a vitreous envelope section sealed between the terminal ring and cathode conductor means, a grid in the envelope connected to said terminal ring, and a cathode in the envelope connected to said conductor means.
- 10 3. An electron tube comprising a sealed-off evacuated envelope, a reentrant metallic external anode forming the upper portion of the tube envelope and having a sealing rim disposed above the lower end of the anode, a grid terminal ring forming part of the envelope wall below said sealing rim, a vitreous envelope section sealed between said rim and terminal ring, cathode conductor means at the lower end of the envelope comprising a tubular stem member and an inner stem member concentric with the tubular member, a vitreous envelope section sealed between the terminal ring and cathode conductor means, a grid in the envelope connected to said terminal ring, and a cathode in the envelope connected to said conductor means.
- 15 4. An electron tube comprising a sealed-off evacuated envelope, a reentrant metallic external anode forming the upper portion of the tube envelope and having a sealing rim disposed above the lower end of the anode, a grid terminal ring forming part of the envelope wall below said sealing rim, a vitreous envelope section sealed between said rim and terminal ring, cathode conductor means at the lower end of the envelope comprising a tubular stem member and an inner stem member concentric with the tubular member, a vitreous envelope section sealed between the terminal ring and cathode conductor means, a grid in the envelope connected to said terminal ring, and a cathode in the envelope connected to said conductor means.
- 20 5. An electron tube comprising a sealed-off evacuated envelope, a reentrant metallic external anode forming the upper portion of the tube envelope and having a sealing rim disposed above the lower end of the anode, a grid terminal ring forming part of the envelope wall below said sealing rim, a vitreous envelope section sealed between said rim and terminal ring, cathode conductor means at the lower end of the envelope comprising a tubular stem member and an inner stem member concentric with the tubular member, a vitreous envelope section sealed between the terminal ring and cathode conductor means, a grid in the envelope connected to said terminal ring, and a cathode in the envelope connected to said conductor means.
- 25 6. An electron tube comprising a sealed-off evacuated envelope having a tubular anode with a hollow cylindrical body projecting from the envelope at one end and a pair of coaxial stem members at the other end, a cooler surrounding said hollow body of the anode and having a cylindrical terminal portion coaxial with the stem members, a terminal ring interposed in the envelope wall between the outer stem member and the anode, a helical cathode in the envelope connected to the stem members, and a tubular grid in the envelope connected to the terminal ring, said cathode and grid and anode having a common axis and said terminal ring and stem members being concentric with said axis.
- 30 7. An electron tube comprising a sealed-off evacuated envelope having a tubular anode with a hollow body projecting from the envelope at one end and having a pair of coaxial stem members at the other end, a terminal ring interposed in the envelope wall between the outer stem member and the anode, a helical cathode in the envelope connected to the stem members, a tubular grid in the envelope connected to the terminal ring, and
- 35 8. An electron tube comprising a sealed-off evacuated envelope having a tubular anode with a hollow body projecting from the envelope at one end and having a pair of coaxial stem members at the other end, a terminal ring interposed in the envelope wall between the outer stem member and the anode, a helical cathode in the envelope connected to the stem members, a tubular grid in the envelope connected to the terminal ring, and
- 40 9. An electron tube comprising a sealed-off evacuated envelope having a tubular anode with a hollow body projecting from the envelope at one end and having a pair of coaxial stem members at the other end, a terminal ring interposed in the envelope wall between the outer stem member and the anode, a helical cathode in the envelope connected to the stem members, a tubular grid in the envelope connected to the terminal ring, and
- 45 10. An electron tube comprising a sealed-off evacuated envelope having a tubular anode with a hollow body projecting from the envelope at one end and having a pair of coaxial stem members at the other end, a terminal ring interposed in the envelope wall between the outer stem member and the anode, a helical cathode in the envelope connected to the stem members, a tubular grid in the envelope connected to the terminal ring, and
- 50 11. An electron tube comprising a sealed-off evacuated envelope having a tubular anode with a hollow body projecting from the envelope at one end and having a pair of coaxial stem members at the other end, a terminal ring interposed in the envelope wall between the outer stem member and the anode, a helical cathode in the envelope connected to the stem members, a tubular grid in the envelope connected to the terminal ring, and
- 55 12. An electron tube comprising a sealed-off evacuated envelope having a tubular anode with a hollow body projecting from the envelope at one end and having a pair of coaxial stem members at the other end, a terminal ring interposed in the envelope wall between the outer stem member and the anode, a helical cathode in the envelope connected to the stem members, a tubular grid in the envelope connected to the terminal ring, and
- 60 13. An electron tube comprising a sealed-off evacuated envelope having a tubular anode with a hollow body projecting from the envelope at one end and having a pair of coaxial stem members at the other end, a terminal ring interposed in the envelope wall between the outer stem member and the anode, a helical cathode in the envelope connected to the stem members, a tubular grid in the envelope connected to the terminal ring, and
- 65 14. An electron tube comprising a sealed-off evacuated envelope having a tubular anode with a hollow body projecting from the envelope at one end and having a pair of coaxial stem members at the other end, a terminal ring interposed in the envelope wall between the outer stem member and the anode, a helical cathode in the envelope connected to the stem members, a tubular grid in the envelope connected to the terminal ring, and
- 70 15. An electron tube comprising a sealed-off evacuated envelope having a tubular anode with a hollow body projecting from the envelope at one end and having a pair of coaxial stem members at the other end, a terminal ring interposed in the envelope wall between the outer stem member and the anode, a helical cathode in the envelope connected to the stem members, a tubular grid in the envelope connected to the terminal ring, and
- 75 16. An electron tube comprising a sealed-off evacuated envelope having a tubular anode with a hollow body projecting from the envelope at one end and having a pair of coaxial stem members at the other end, a terminal ring interposed in the envelope wall between the outer stem member and the anode, a helical cathode in the envelope connected to the stem members, a tubular grid in the envelope connected to the terminal ring, and

a cooler having fins disposed about said hollow body of the anode, said cathode and grid and anode having a common axis and said cooler and terminal ring and stem members being concentric with said axis.

7. An electron tube comprising a sealed-off evacuated envelope having a tubular external anode with a hollow cylindrical body projecting from the envelope at one end and a pair of coaxial stem members at the other end, a cooler surrounding said hollow body of the anode and having a cylindrical terminal portion coaxial with the stem members, a terminal ring interposed in the envelope wall between the outer stem member and the anode, a filamentary cathode connected to and supported wholly by said stem members, and a grid connected to and supported wholly by said terminal ring.

8. An electron tube comprising a sealed-off evacuated envelope having a tubular external anode with a hollow cylindrical body projecting from the envelope at one end and a pair of coaxial stem members at the other end, a cooler surrounding said hollow body of the anode and having a cylindrical terminal portion coaxial with the stem members, a terminal ring interposed in the envelope wall between the outer stem member and the anode, a center rod on the inner stem member projecting upwardly into the anode,

a filamentary cathode supported at the top by the center rod and at the bottom by the outer stem member, and a grid connected to the terminal ring.
